UNITED STATES PATENT OFFICE.

WILLIAM W. CALDWELL, OF CHICAGO, ILLINOIS.

BUSINESS-CARD.

SPECIFICATION forming part of Letters Patent No. 415,380, dated November 19, 1889.

Application filed January 18, 1889. Serial No. 296,715. (No model.)

To all whom it may concern:

Be it known that I, WILLIAM W. CALDWELL, a citizen of the United States, residing at Chicago, in the county of Cook and State 5 of Illinois, have invented certain new and useful Improvements in Business-Cards, of which the following is a specification.

My said invention relates to an improved construction and arrangement of business-10 cards, whereby, in addition to the usual use of a business-card, a convenient and effective means is provided for a more extensive advertisement of the business represented; and it consists in constructing said business-15 cards in the form of an article, preferably incorporating a calendar, of use and value for reference and information, as will be herein-after more fully described and claimed.

Referring to the accompanying drawings, 20 which are made a part hereof, and on which similar letters of reference indicate similar parts, Figure 1 is a perspective view showing one side of a card of my improved construction; Fig. 2, a similar view of its other side, 25 and Fig. 3 a view showing the two parts of which it is composed separately.

In said drawings the portions marked A represent the "jacket" or envelope, which forms the outside of the card, and B the 30 "folder," which forms its inside portion.

The jacket A is formed of any suitable material for the purpose and of any size which may be desired for the proposed card, and is preferably formed with both ends open, as 35 shown. On one side is printed the desired business-card, as indicated in Fig. 1, and on the other side is printed a table of figures arranged to indicate the days of the month. The preferable arrangement of this table consists of five vertical columns of seven 40 numbers each, counting from the top to the bottom, commencing at the left-hand column; but other arrangements might be devised that would be equally useful in accomplishing the 45 purpose of my invention. Above said table of figures is arranged a table of the names of the first days of each month of several successive years, by which the information needed in "setting" the calendar for each month can 50 readily be found. Along the side of the table of figures a slot or opening a is formed in

the jacket, through which the days of the week arranged on the folder within can be seen. Below said table of figures is printed any matter desired, but preferably something 55 referring to the contents of the folder within, as indicated in Figs. 2 and 3.

The folder B is shown as a four-page circular, but of course may consist of as many pages as desired. It is formed to fit closely 60 within the jacket A, and along its left-hand margin is printed a column b, containing the names of the days of the week, preferably arranged, as indicated, with full sets of the names, seven of which fill the space or opening a in 65 the jacket, and each being arranged opposite one of the numbers in the column by its side. The other space upon the folder can be filled with any reading matter desired, either of an advertising or instructive character—such 70 as tables for computing interest, census-tables, current statistics, and other valuable information for which the card would probably be preserved by the majority of people into whose hands it would fall. In addition to 75 such instructive or useful information, considerable advertising matter relating to the business represented could easily be given a place in the folder without destroying its use and value. 80

In addition to the features particularly described above is the feature of a perpetual calendar, convenient for pocket use, which is thus provided, and which is used as follows: To set the calendar, the table at the top of the 85 rear side of the jacket is first referred to, the month for which the calendar is to be set being found in the left-hand column, and the day opposite this month is found in the column headed by the number of the current 90 year. The folder B is then slid in the jacket until the name of the day thus found is brought to a position directly opposite to the figure 1 in the table, it being considerably shorter than the jacket, so that its ends will 95 not project therefrom when it is slid back and forth. Thus the calendar can be set for any month of any year with but a moment's time, and in a manner so simple that any one can readily use it. Different designs and arrangements of the card both as to the information given and its other contents can, of course, be 100

- made without departing from my invention. By this arrangement a card is provided of such a useful and valuable character, by reason of the extremely convenient pocket-calendar 5 which it affords, and also the valuable reference-tables and other instructive matter which comprise the contents of the folder B, that it is rendered of such value that its preservation and frequent reference thereto are 10 assured, and the name of the advertiser and his business thus become firmly fixed in the mind of the person to whom the card is given, while an ordinary card would be referred to but once and its contents readily forgotten.
- 15 Having thus fully described my said invention, what I claim as new, and desire to secure by Letters Patent, is—
1. A combined card and calendar, consisting of a jacket having a table indicating the 20 days of the month thereon and an opening alongside said table, and a part formed to fit within said jacket and formed with a column containing the names of the days of the week arranged to register with the opening in said jacket, substantially as set forth.
  2. In a combined card and calendar, the 25 combination of the jacket A, having the tables indicated in Fig. 2 formed upon one side thereof, the opening a, and the folder B, 30 mounted within said jacket and provided

with the column b, containing the names of the days of the week and printed matter of a useful and advertising character, substantially as set forth.

3. A combined card and perpetual calendar consisting of a jacket having the table indicating the days of the month thereon, an opening alongside said table, and a sliding part within said jacket containing the names of the days of the week arranged in a column 35 40 to register with said opening, substantially as set forth.

4. As a new article of manufacture, a combined card and calendar formed in a jacket form, having an opening in one side and a 45 portion of a perpetual calendar alongside said opening, and a sliding part within said jacket having the other portion of the perpetual calendar formed thereon, whereby a business-card having a perpetual calendar as one feature thereof is secured, substantially as set forth.

In witness whereof I have hereunto set my hand and seal, at Chicago, Illinois, this 11th day of January, A. D. 1889.

WILLIAM W. CALDWELL. [L. S.]
